UNITED STATES PATENT OFFICE.

CLARENCE T. EVANS, OF MILWAUKEE, WISCONSIN, ASSIGNOR TO THE CUTLER-HAMMER MFG. CO., OF MILWAUKEE, WISCONSIN, A CORPORATION OF WISCONSIN.

TENSION DEVICE.

1,343,910.

Specification of Letters Patent. Patented June 22, 1920.

Application filed May 28, 1914. Serial No. 841,613.

To all whom it may concern:

Be it known that I, CLARENCE T. EVANS, a citizen of the United States, residing at Milwaukee, in the county of Milwaukee and 5 State of Wisconsin, have invented new and useful Improvements in Tension Devices, of which the following is a full, clear, concise, and exact description, reference being had to the accompanying drawing, forming 10 a part of this specification.

This invention relates to improvements in tensioning devices and is particularly applicable to printing presses, although it may 15 obviously be advantageously employed in other relations.

The invention has among its objects to provide means automatically tending to maintain the web or other material supplied to the receiving machine under given tension at all times.

A further object is to provide means of the aforesaid character which will act upon relatively slight variations in tension and which will also act with varying rapidity according 25 to the degree of tension variation.

Various other objects and advantages of the invention will hereinafter appear.

The invention may, in practice, be embodied in various different forms, one of 30 which has been schematically illustrated in the accompanying drawing.

Referring to the drawing, the same shows a roll 1 of web or other suitable material to be fed to a press or other receiving machine, exemplified by cylinders 2. As the 35 material is withdrawn from the roll 1 it is passed over a yielding fixed roll 3, then beneath an adjustable roll 4 and over a second fixed roll 5 to the press or other machine 2.

40 The adjustable roll 4 constitutes a tension device automatically adjustable to different positions according to the amount of slack between the rolls 3 and 5. It is carried by a frame 6 pivotally supported by a bracket 7 and connected by a spring 8 to an adjustable device 9. The spring 8 biases the tension roll 4 downwardly against the web, thereby tensioning the latter and the device 9 affords means for adjusting the spring to 45 provide any desired tension at a given angle of the frame 6. As shown, the frame 6 is in normal position and is movable in opposite directions therefrom upon positive and negative variations in the slack of the web.

Such movement of the tension roll, of course, 55 varies the tension of the web and the following means are provided to rectify such variations and thereby tend to maintain the given tension.

The core or shaft of the roll 1 is connected 60 as by a belt 10 to the armature A of a shunt wound dynamo-electric machine M. The machine M has a shunt field winding F and is adapted to act either as a generator to electrically brake the roll or as a motor to drive 65 said roll and is governed by a rheostat R. The rheostat R is in turn automatically controlled by the movement of the tension device 4 to govern the machine M in accordance with the movement of said device for 70 the purposes hereinafter set forth.

The rheostat has a pivoted arm 13 operatively connected, as by means of a belt 14, to a shaft 15, in turn operatively connected to a driving shaft 16 through a worm 17 75 and worm wheel 18. The shaft 16 is mounted in bearings 19 and has splined thereto a friction wheel 20 co-operating with a friction disk 22 rotatable with the web roll 1, although if preferred said disk may be 80

driven from some other source, as, for example, the press or independent means. The arrangement is such that the friction wheel 20 is movable longitudinally of the shaft 16 and diametrically across the disk 22 to establish a reversible drive from the disk 22 to the shaft 16 and to vary the speed ratio between said members. For effecting such movement of the friction wheel the same is provided with an operating lever 23 ful- 90

crumed to a bracket 24 and connected by a link 25 to a bell crank extension 26 of the tension frame 6. The arrangement is such that in normal position of the frame 6 the friction wheel 20 is disposed centrally of 95 the friction disk to be inert. When, however, the tension device moves in either direction from its normal position it moves the friction wheel in a corresponding direction radially of the friction disk and to a degree 100 proportional to the degree of movement of said tension device. Accordingly, the rheostat R is thereby operated in one direction or the other according to the movement of said tension device and at a speed varying with 105 and proportional to the degree of movement of said tension device. More specifically as the tension device falls it effects movement

of the rheostat arm in a clockwise direction and as it rises effects movement of the rheostat arm in a counter-clockwise direction.

The rheostat arm carries contacts to electrically connect a contact segment 27 with any one of a series of contact buttons 28, said buttons being connected to a resistance r for the armature of the machine M. The arm 13 in its dotted line position connects all of the resistance r in series with the armature A and also connects a resistance r' in parallel with said armature. Then as the arm moves in a counter-clockwise direction it gradually changes the resistance r from series to parallel relation with respect to the armature. As is well understood, this tends to cause the machine to act as a motor, while reverse operation of the rheostat tends to slow down the machine and when it is overhauled by its load to cause it to act as a dynamic brake.

The mechanism as a whole operates as follows: Assuming that the web is being drawn into the press under the desired tension with the rheostat arm in the position illustrated, the machine M will act as a generator, being driven by the roll and therefore act as a dynamic brake for the roll. Under such conditions, should the press slow down, causing an increase in slack with a consequent dropping of the tension roll, the friction wheel would be moved to the right, thereby effecting clockwise movement of the rheostat arm. This would result in an increase of the series resistance and a decrease of the shunt resistance, which would further increase the braking effect of the machine M to slow down the web roll. If the increase in slack was large the tension device would cause a relatively large movement of the friction wheel with a consequent accelerated speed of the rheostat. On the other hand, if the increase in slack was slight, then the movement imparted to the friction wheel would be proportionally slight and the speed of the rheostat proportionally low. Thus the action of the rheostat is suited to the need and as the roll is slowed down and the excessive slack taken up the friction wheel is returned toward neutral position to gradually slow down and stop the rheostat arm. However, the rheostat arm is stopped only when the tension device is restored to normal position, with a consequent restoration of normal tension. After restoration of normal tension the rheostat arm remains inert until the tension device again falls or rises.

Assume now that the slack in the web decreases either through an increase in the speed of the press or a decrease in the size of the roll. Under such conditions the tension device would be raised with a resulting operation of the rheostat in a counter-clockwise direction. This, as above set forth, would decrease the braking effect of the

machine M, permitting the web roll to accelerate. Also, as above set forth, this movement of the rheostat in this direction tends to cause the machine M to act as a motor. Hence, should the elimination of the braking effect fail to effect restoration of normal conditions, then said machine would act as a motor to drive the roll. This action, however, would be unlikely to occur unless the roll had been reduced to a relatively small diameter. Again, it will be observed that the rheostat is operated at a speed proportional to the degree of movement of the tension device, and is gradually slowed down and stopped as the tension device returns to normal position.

Hence, throughout the feeding of the web the mechanism would pass through one or the other of the aforesaid cycles of operation upon each variation in tension, thereby tending at all times to maintain the tension at the desired predetermined value.

Assume now that the press is stopped, or that the web breaks. Under such conditions there is a tendency for the roll, especially if large, to continue to rotate. This would result in an increased slack with a consequent dropping of the tension device and operation of the rheostat in a clockwise direction. This, in turn, would gradually increase the effectiveness of the machine M as a brake and, if the momentum of the roll was sufficient, would return the rheostat to dotted line position, giving the maximum braking effect. Quick stopping of the roll would thereby be insured.

In restarting the roll 1 the machine M, of course, acts according to the position of the rheostat and hence according to the position of the tension roll 4. However, it always permits the roll to be readily started, for, even in braking position of the rheostat said machine has no braking effect upon the roll until after the latter is set in motion.

What I claim as new and desire to secure by Letters Patent is:

1. In a tension mechanism for printing press rolls and the like, in combination, a mechanism having a positive power connection with the roll and operative through said connection for driving and braking the roll selectively and a governor operable in accordance with variations in tension of the material delivered by the controlled roll for varying the action of said mechanism. 110

2. In a tension mechanism for printing press rolls and the like, in combination, means for selectively driving and braking the roll and governing means therefor responsive to variations in the slack of the material drawn from the roll, said latter means selecting the action of said former means and varying the action thereof according to both the character and degree of slack variation. 125

3. In a tension mechanism for printing press rolls and the like, in combination, a dynamo-electric machine having a positive power connection with the roll, and automatic governing means therefor responsive to variations in tension of the material supplied from the roll to cause said machine to act alternatively as a driver or as a brake for the roll.
- 10 4. In a tension mechanism for printing press rolls and the like, in combination, a dynamo electric machine having an operative connection with the roll and automatic controlling means therefor responsive to variations in the slack of the material drawn from the roll to cause said machine to act alternatively as a driver or as a brake according to the character of the slack variations.
- 15 5. In a tension mechanism for printing press rolls and the like, in combination, a dynamo-electric machine having an operative connection with the roll and automatic controlling means therefor responsive to variations in the slack of the material drawn from the roll to cause said machine to act alternatively as a driver or as a brake according to the character of the slack variation and to a degree corresponding 30 with the degree of slack variation.
6. In a tension mechanism for printing press rolls and the like, in combination, means for alternatively driving or braking the roll and means responsive to variations 35 in the slack of the material drawn from the roll to vary the action of said former means and to maintain the variation thus effected during restoration of normal slack and until subsequent variation thereof.
- 40 7. In a tension mechanism for printing press rolls and the like, in combination, means for alternatively driving or dynamically braking the roll and governing means therefor responsive to variations in the tension to act thereon in reverse ways but selectively according to the character of tension variation from a given value.
- 45 8. In a tension mechanism for printing press rolls and the like, in combination, means for alternatively driving or braking the roll, a slack device, and governing means for said driving or braking means operable in reverse directions in response to movement of said slack device but uni-directional 50 within certain ranges of said device irrespective of the direction of movement of the latter.
9. In a tension mechanism for printing press rolls and the like, in combination, a 55 dynamo-electric machine having an operative connection with the roll and automatic means responsive to tension variations to cause said machine to act alternatively as a driver or as a brake, said means upon 60 effecting an adjustment of said machine in response to a tension variation maintaining such adjustment during restoration of normal tension and until a subsequent variation in tension.
10. The combination with tensioning means for material drawn from a roll, of a dynamo-electric machine operatively connected to the roll of material to dynamically 70 brake the same and governing means for said machine automatically operable upon variations in the slack in the web.
11. The combination with tensioning means for material drawn from a roll, of a dynamo-electric machine operatively connected to the roll of material to electrically 75 brake the same and governing means for said machine automatically operable upon variations in tension and in either of two ways according to the character of the tension variation.
12. In combination, tensioning means for material drawn from a roll, a dynamo-electric machine operatively connected to the roll to drive or dynamically brake the same selectively and controlling means for said 80 machine operable automatically upon variations in tension and in different ways and at different speeds according to the character and degree of tension variation.
13. In combination, tensioning means for material drawn from a roll, a dynamo-electric machine operatively connected to the roll of material and a power and dynamic braking controller for said machine governed in operation by movement of a part of 90 said tension device.
14. In combination, tensioning means for material drawn from a roll, a dynamo-electric machine operatively connected to the roll of material, a power and dynamic 95 braking controller for said machine and operating means for said controller governed in speed and direction of operation by movement of a part of said tension device.
15. In combination, tensioning means for material drawn from a roll, including a device automatically adjustable upon variations in slack, a dynamo-electric machine operatively connected with the roll of material, a power and dynamic braking controller for 100 said machine and operating means for said controller governed by said adjustable device.
16. In combination, tensioning means for material drawn from a roll, including a device automatically adjustable upon variations in slack, a dynamo-electric machine operatively connected with the roll of material, a power and dynamic braking controller for 105 said machine, automatic operating means 110 for said controller and direction and speed controlling means for said latter means actuated by said adjustable device.
17. In combination, tensioning means for material drawn from a roll, including a de- 115

vice automatically adjustable upon variations in tension and to a degree proportional to the tension variation, a dynamo-electric machine operatively connected to the roll of material, a power and dynamic braking controller for said machine and operating means for said controller ineffective in a given position of said device and rendered effective upon movement of said device from said given position.

18. In combination, tensioning means for material drawn from a roll including a device automatically adjustable upon variations in tension and to a degree proportional to the tension variation, a dynamo-electric machine operatively connected to the roll of

material, a power and dynamic braking controller for said machine and means whereby said controller is operated in different directions and at varying speeds upon movement of said device in opposite directions from a given position and is rendered inert when said device assumes said given position. 20

In witness whereof I have hereunto subscribed my name in the presence of two witnesses. 25
